UNITED STATES PATENT OFFICE.

BERNICE J. NOYES, OF BOSTON, AND HOWARD F. EATON, OF CAMBRIDGE, MASSACHUSETTS.

LIGHT-SIGNAL SYSTEM.

SPECIFICATION forming part of Letters Patent No. 450,182, dated April 14, 1891.

Application filed April 5, 1889. Serial No. 306,074. (No model.)

To all whom it may concern:

Be it known that we, BERNICE J. NOYES, of Boston, county of Suffolk, and HOWARD F. EATON, of Cambridge, county of Middlesex, 5 State of Massachusetts, have invented an Improvement in Light-Signal Systems, of which the following description, in connection with the accompanying drawings, is a specification, like letters on the drawings representing like parts.

This invention has for its object to construct and arrange a light-signal system especially adapted for police-signaling purposes.

15 In accordance with this invention the several light-signals are included in a single circuit, the light-signals being designed to be operated independently, and at each light-signal station a code-return-signal transmitter is provided, which, when operated, transmits to the receiving-station its signal or number. As herein represented, the code-return-signal transmitter consists of a normally-wound motor and a circuit-wheel, and a releasing-magnet is employed to release the same. An other releasing-magnet is employed to release the light-signal. The code-return-signal-transmitter-releasing magnet is designed to be operated first to make known at the central station whether or not the correct number or 25 sub-station is in condition for its light-signal to be released, and if found to be correct the light-signal is then released. An additional circuit-changing device is arranged at each 30 sub-station to make known or indicate at the central station that the operation of the light-signal has been successful, thereby avoiding mistakes.

Figure 1 shows in diagram a light-signal 40 system embodying this invention; Fig. 2, a detail showing a light-signal such as may be employed; and Fig. 3, a diagram of a modified form of light-signal system, the code-return-signal transmitters being omitted.

45 The main circuit A includes a central station B and several light-signal stations. Each light-signal station contains an individual call, (shown as a step-by-step device consisting of an electro-magnet a,) the armature a' of which is secured to one end of a lever a'',

pivoted at a³, the opposite end of said lever carrying a push-pawl a⁴, which engages the teeth of a ratchet-wheel a⁵, fixed to the shaft a⁶. A spring-controlled back-stop a⁷ is provided to permit only forward rotation of the ratchet-wheel in the direction of the arrow shown. At the central station a circuit-controlling device is provided, herein shown as consisting of a circuit-wheel b, contact-pen b', included in the main line A, and motor mechanism for revolving the circuit-wheel b, a pointer or arm b², and a face-plate in which holes b³ are formed, into one of which a stoppin b⁴ may be placed, with which the pointer or arm b² co-operates to stop the circuit-wheel 55 at definite points. As the circuit-wheel is revolved the electro-magnet and its armature carrying lever operate to move the ratchet-wheel a⁵ one tooth for each impulse. A circuit-wheel c is also fixed to the shaft a⁶, 70 having an insulated portion, and a pen c' bears on the wheel c, the said wheel and pen being connected by wires 2 3 with the main line A. The circuit-wheel c of each light-signal station is placed upon the shaft a⁶ differently, or so that a different number of impulses may be required to bring the circuit-wheel c of each light-signal station into position, so that the pen c' will bear upon the insulated portion thereof. A releasing-magnet d is included in the main circuit A, the armature-carrying lever d' of which is acted upon or has co-operating with it a retarding device, herein shown as a sector d², pinion d³, escape-wheel d⁴, and pallet d⁵. The armature-carrying lever d' has a tooth d⁶, which enters a notch in a wheel d⁷ of a normally-wound motor mechanism. The releasing-magnet d is included in the main line A between the wires 75 2 3, so that it is normally shunted out by the circuit-wheel c, pen c', and wires 2 3. A circuit-wheel e is attached to a shaft of the normally-wound motor mechanism C, said circuit-wheel being driven by the said motor when released and being formed to transmit 80 a code-signal indicating the number of the light-signal station. As herein shown, the circuit-wheel e is included in a ground tap or branch 4, and the pen 5 co-operating with the said circuit-wheel is also included in the 85 90 95 100

90 95 100

ground tap or branch 4 from the main line, said tap or branch being normally open and designed to be closed by the circuit-wheel as the latter is revolved.

5 In operation, as the transmitter at the central station is operated, the circuit-wheel *c* of all the light-signal stations revolves step by step, and the releasing-magnets *d* are thereby included successively for a short period of 10 time. When the arm or pointer *b*² strikes the pin or stop *b*⁴, the insulated portion of the circuit-wheel *c* at one of the stations (herein shown as station No. 4) will be beneath the pen *c*', thereby opening the shunt and including the releasing-magnet *d* until the pin or stop *b*⁴ is removed. This period of time will be sufficient to enable the armature of the releasing-magnet *d* to be attracted toward and against the poles of the magnet, thereby 15 releasing the motor mechanism *C* and rotating the circuit-wheel *e*. At the central station a closed ground-tap 6 leads from the main line *A*, it including the battery 7 and receiving-magnet *f*. The armature-carrying lever *f*' of 20 the magnet *f* controls a local circuit *f*², including the local battery *f*³, and the register or other receiving instrument *f*⁴ and as 25 the circuit-wheel *e* successively closes the ground tap or branch 4 the number transmitted by said circuit-wheel will be received. At the central station a pole-changing key or 30 battery-reversing instrument *D* is employed, and at each light-signal station a polarized releasing-magnet *i* is included in the main 35 line *A*, but normally shunted out by the circuit-wheel *c*, pen *c*', and wires 2 3, but is included simultaneously with the releasing- 40 magnet *d* to be responsive. After the return-signal transmitter *C* has been released and 45 its signal transmitted to the central station that it may be known that the correct light-signal has been included in the line the pole-changing key or battery-reversing instrument *D* is operated, effecting the movement of the 50 armature-carrying lever *i*' of the polarized releasing-magnet *i*, thereby releasing the rod *i*². The rod *i*² is or may be connected with or formed as a part of the vertically-movable light-signal, (see Fig. 2,) being herein 55 represented as a colored globe on the rod *i*², which is adapted to be raised by a spring to inclose the flame. The rod *i*² is designed to move upward and is provided with a projection *i*³, (see Fig. 1,) which, as it approaches 60 the limit of its upward motion, engages a projection *i*⁴ of a bar *i*⁵, carrying a pen *i*⁶, which co-operates with a contact-surface *i*⁷. The pen *i*⁶ and its signaling-surface *i*⁷ are included in branch wires 8 9 of the ground-tap, 65 so that when the light-signal arrives in its most elevated position or is displayed the receiving apparatus at the central station will again respond. It will be seen that by this construction and arrangement any light-signal of a number may be operated from the central station independently, the number of

the station may be received previous to the light-signal being displayed, and a return-signal also received after the signal has been displayed, so that no mistakes can be made. 70

It is obvious that the releasing-magnet *d* herein shown may be employed to release the light directly, the return-signal-transmitting devices being omitted, as illustrated in Fig. 3, and the retarding device being supplied, so 75 that the armature will only be moved to release the light-signal on a long closure of the circuit. It is also obvious that any other independent or individually-operating device may be employed to operate the releasing or operating magnet for the light-signal in conjunction with return-signal-transmitting devices, so we do not desire to limit our invention to the precise construction and arrangement shown. 80

We have herein shown, in addition to the devices above described, a well-known form of unison, it consisting of the polarized electro-magnet *n*, locking-armature *n*' of which carries the fork *n*², between the tines of which 90 the swiveled and hinged bar *n*³ is held, said bar having a pin which follows in a spiral groove of a hub *n*⁴, which groove is also provided with a stop-pin *n*⁵.

To render the polarized electro-magnet *n* 95 non-responsive when it is desired to operate the polarized electro-magnet *i*, a disk *m* is fixed to the shaft *a*⁶, it having a single projection which engages the pen *m*' at the moment the shunt *c* 2 3 is open, said disk and arm *m* *m*' being connected by wires 12 13 with the main line *A* around the polarized electro-magnet *n*, to thereby shunt it out. In Fig. 3 this polarized magnet *n* is employed; but it is included directly in the circuit, and 100 the battery-reversing instrument *D* is employed to operate it. 105

I claim—

1. In a light-signal system, an electric circuit including a central station and several 110 light-signal stations, each light-signal station containing a light-signal and magnet for effecting its operation, also a normally-wound return-signal transmitter and magnet for releasing it, and also an individual-call switch 115 for rendering operative both of said magnets, and the central station containing a circuit-controller for the individual-call switches, and a return-signal receiver and a circuit-controlling device for the light-signal-operating magnets, substantially as described.

2. In a light-signal system, an electric circuit including a central station and several light-signal stations, a circuit-controller at the central station, and individual-call switches 125 at the light-signal stations, combined with a light-signal and also a code-return-signal transmitter at each light-signal station, both of which are governed by the individual-call switch thereat, and a signal-receiving instrument at the central station for the return-signals, and a circuit for said code-return-signal 130

transmitter and its receiver, which excludes the operating-magnets of the individual-call switches, substantially as described.

3. In a light-signal system, the main electric circuit including the central station and several light-signal stations, light-signals at the said stations operable independently, combined with return-signal transmitters at the light-signal stations, normally-wound motors therefor, and releasing-magnets, the armatures of which control the said normally-wound motors, and a retarding or restraining device for said armatures, whereby the said return-signal transmitters may be released 15 when its releasing-magnet is included in the circuit a long period of time, and signal-receiving instruments at the central station for said return-signals, substantially as described.

4. In a light-signal system, an electric circuit including a central station and several light-signal stations containing light-signals, combined with two code-return-signal transmitters at each light-signal station, one of which indicates the number of the station 25 and the other the operation of the light-signal, and means controlled from the central station for operating them, and a signal-receiver at the central station for the return-signals, substantially as described.

5. In a light-signal system, an electric circuit including a central station and several light-signal stations containing light-signals, combined with means for operating the light-signals, and a code-return-signal transmitter 35 at each light-signal station controlled by the light-signal when operated, and another code-return-signal transmitter at each light-signal station controlled by an independent device for indicating the number of the light-signal 40 station, substantially as described.

6. In a light-signal system, an electric circuit including a central station and several light-signal stations, combined with a circuit-controller at the central station, an operating-magnet at each light-signal station, a shunt- 45

switch controlled by said operating-magnet, an electro-magnet, as d , in the circuit controlled by said shunt-switch, and a retarding device for the armature of said magnet d , said retarded armature controlling the operation of the light-signal, substantially as described. 50

7. In a light-signal system, an electric circuit including a central station and several light-signal stations, a circuit-controller at 55 the central station, and individual - call switches at the light-signal stations, combined with a light-signal and also a code-return-signal transmitter at each light-signal station, both of which are governed by the individual-call switch thereat, and a signal-receiving instrument at the central station for the return-signals, and a circuit-controlling device also at the central station for co-operating with said individual-call switch to effect the 60 operation of the light-signal system, substantially as described. 65

8. In a light-signal system, an electric circuit, including a central station and several light-signal stations, a circuit-controller at 70 the central station, and individual - call switches at the light-signal stations, combined with a light-signal and also a code-return-signal transmitter at each light-signal station, both of which are governed by the individual-call switch thereat, and a signal-receiving instrument at the central station for the return-signals, the said code-return-signal transmitter transmitting impulses of different character from that employed to operate 75 the individual-call switches, substantially as described. 80

In testimony whereof we have signed our names to this specification in the presence of two subscribing witnesses.
